[57] CLAIM

The ornamental design for a combined handle and escutcheon for doors or windows, as shown and described.

DESCRIPTION

FIG. 1 is a front view of a combined handle and escutcheon for doors and windows showing my new design;

FIG. 2 is a right side view thereof;

FIG. 3 is a left side view thereof;

FIG. 4 is a plan view thereof;

FIG. 5 is a bottom view thereof;

FIG. 6 is a perspective view thereof;

FIG. 7 is a front view of an alternate embodiment of my new design;

FIG. 8 is a right side view thereof;

FIG. 9 is a left side view thereof;

FIG. 10 is a plan view thereof;

FIG. 11 is a bottom view thereof;

FIG. 12 is a perspective view thereof;

FIG. 13 is a front view of an alternate embodiment of my new design;

FIG. 14 is a left side view thereof;

FIG. 15 is a right side view thereof;

FIG. 16 is a plan view thereof;

FIG. 17 is a bottom view thereof; and,

FIG. 18 is a perspective view thereof.
